United States Patent

Des. 241,162
Patented Aug. 24, 1976

241,162

RECORD PLAYER

Irwin J. Lubalin, Rockville Centre, N.Y., assignor to
Avnet, Inc., New York, N.Y.

Filed Dec. 23, 1974, Ser. No. 535,426

Term of patent 14 years

Int. Cl. D14—01

U.S. Cl. D56—4 R

FIG. 1 is a front, top and right side perspective view of a record player showing my new design;

FIG. 2 is a top plan view; and

FIG. 3 is a rear elevational view with the record spindle shown as broken off for convenience of illustration.

I claim:

The ornamental design for a record player, as shown and described.
